AIRPLANE

Kenneth Robert Bailey, Dearborn, Mich.

Application November 8, 1950, Serial No. 12,911

Term of patent 14 years

(Cl. D71—1)

To all whom it may concern:

Be it known, that I, Kenneth R. Bailey, a citizen of the United States, residing at Dearborn, Wayne County, Michigan, have invented a new, original, and ornamental Design for an Airplane, of which the following is a specification, reference being had to the accompanying drawings, forming a part thereof, in which:

Figure 1 is a perspective view of an airplane, showing my new design.

Figure 2 is a side elevational view of the airplane;

Figure 3 is a top view of the airplane;

Figure 4 is a front elevational view of the airplane with the wings extended in their operative flying position;

Figure 5 is a front elevational view of the airplane as it appears with its wings folded inwardly; and

Fig. 6 is a rear elevation of the airplane as it appears with its wings folded outwardly.

The characteristic features of my design reside in the parts shown by means of full lines in the drawing.

I claim:

The ornamental design for an airplane, as shown and described.

KENNETH ROBERT BAILEY.
